UNITED STATES PATENT OFFICE

RICHARD F. SCHULZKE, OF PORTLAND, OREGON

IRONING TABLE

Application filed June 21, 1928. Serial No. 287,161.

The object of my invention is to provide an inexpensive ironing table mounted upon a collapsible supporting frame, which, when set up, is extremely rigid and which collapses into a minimum space.

A more specific object of my invention is to provide an ironing table of this character with a convenient iron holder arranged at one end of such board, such iron holder serving to furnish such latter end with a convenient gripping element for moving the table about, and for holding the same while setting up or collapsing such support.

The details of construction and operation of an ironing table embodying my invention are illustrated in the accompanying drawings: in which,

Fig. 1 is a side elevation of such table with portions broken away to show the locking device for holding such table rigidly extended;

Fig. 2 is a longitudinal section thru such table in collapsed position;

Fig. 3 is a plan view of such table looking from underneath, with the supports collapsed;

Fig. 4 is a fragmentary detail of the locking device; and

Fig. 5 is a fragmentary detail of the iron holder.

My improved ironing table comprises a board *a* mounted upon a collapsible support. Such support comprises a rear leg structure *b*, composed of two spaced members *b'* connected by two horizontal slats *c* and *c'* and reinforced by slats *c²* and *c³* extending substantially longitudinally of such leg structure *b*, and a diagonal crutch *d*, also made up of two converging members *d'*. Such members *b* and *d* are pivotally connected to the rear end of the ironing board, being fastened thereto by cleats *e* depending from the under surface of such board and extending substantially longitudinally thereof. A shaft or pivot pin *f* extends transversely of such board thru such cleats and serves as a common pivot connection for the ends of both such members *b* and *d*. The converging members *d'* of the diagonal crutch *d* are secured at their point of convergence by a

threaded screw *g* and are spaced apart adjacent such screw by a spacer *h*. Near the diverging end of such crutch is another spacer *h'*. Between such spacers *h* and *h'* are two spaced guide rods *i* extending laterally of such crutch and defining a groove *i'* between them. A jointed brace member *j* serves to hold the various members of the ironing board in rigid extended position and the ends of such jointed brace members are pivotally fastened to the under surface of the board *a*, and the leg *b* respectively. The pivotal connection between the end of the jointed brace member *j* and the board *a* is made thru two downwardly depending cleats *k* fastened to the under surface of the board *a* at substantially its middle. Such cleats are connected to the end of the member *j* thru a pivot pin *k'*. The opposite end of such jointed brace member *j* is connected to the leg *b* by a pivot pin *l* extending thru such end and thru the reinforcing slat members *c* and *c'*. One element *j'* of such jointed brace member *j* extends substantially horizontally when the table is arranged in set-up position and extends thru the groove *i'*. The other element *j''* of such brace member extends substantially vertically and such members *j'* and *j''* are connected by an integral fitting *m*. Such fitting *m* is substantially U-shaped in section, thus forming a channel, and such fitting *m* straddles the member *j'*, the webs *m'* of such fitting extending downwardly along the sides of the member. Such webs are substantially longer than the thickness of the member *j'* and the portions extended beyond the under-surface of such member carry a bayonet joint *n* therein, as is shown in Fig. 4. The member *j'* is cut away at *n'* in registration with the portion of such joint *n*, which overlies such member *j'*. Upstanding integral ears *m''* are arranged upon the back of such fitting and a pivot pin *o* extends thru such ears and thru the member *j''* to pivotally connect the members of such jointed brace. Such bayonet joint *n* is adapted to engage the lowermost rod *i* defining the groove *i'* when the parts are arranged in set-up position, and a spring-like keeper *p* also engages

such lowermost rod *i* and holds the same in the portion *n'* of such bayonet joint. Such keeper preferably is made of a spring-like leaf carried by the member *j'*. Two screws 5 *q* fasten such keeper to the member *j'*, the screw *q'* being adjustable to vary the pressure exerted by such keeper and thus to vary the amount of pressure necessary to unseat the member *i* and to collapse the table.

10 A recess *r* is formed at the rear end of the ironing board *a*, entering such end approximately equi-distant from the sides thereof. A marginal shoulder *s* is formed about such recess and heat resisting material *t*, such for 15 example as asbestos, is arranged upon such shoulder *s*. An iron holder *u* is carried in such recess with the outstanding edges supported upon such heat resisting material and recessed so that the upper face of the iron holder is substantially flush with the active surface of the ironing board *a*. Nails *v* fasten the iron holder in place in such recess. Such iron holder *u* has a depressed portion *u'* formed therein forming a receptacle 20 for the iron. The end *u''* of such holder extends downwardly over the end of the ironing board *a* and is bent back upon itself to engage the under surface thereof, as is shown in Fig. 2, thus virtually clamping the ironing board between the two spaced parallel portions. Such iron holder is made of an 25 integral stamping and the portions are arranged so that the burrs formed by such stamping can be arranged to face the ironing board both on the top as well as on the bottom and thus such iron holder does not have to be dressed to remove such burr, which is quite sharp. This is one of the more 30 important advantages attained by the bending over of the rear portion of the iron holder. Such bent-over portion *u''* also serves solidly to connect the iron holder to the board without depending upon nails. Such iron holder frequently is used as a gripping element 35 for moving such iron board about, when setting up or collapsing the table and thus unless such iron holder is securely fastened to the board it will be unseated. Unseating permits the asbestos or other heat resisting 40 material to shift from off the shoulder and to become lost so that the heat transmitted by the metal iron holder *u* chars the wood and destroys its seat in the board.

The operation of my board is as follows:

45 With the board arranged in collapsed position, as shown in Fig. 2, the parts can be moved into set-up position by rotating the members *b* and *d* counter-clockwise about the pivot *f* relatively to the board *a*. The jointed 50 brace is automatically pulled into position and the locking device or keeper is seated because the member *j'* is maintained to substantially linear movement by the relatively close fitting guiding groove *i'*. The continued rotation counter-clockwise of such members *b* and

d automatically locks the parts. To unlock the locking device, pressure is applied between the free ends of the crutch and the ironing board which lifts the lower member *i* from out of the portion *n'* of the bayonet 70 joint *n*, so that the leg *d* can be swung clockwise about its pivot, as viewed in Fig. 1. The parts are then free to continue the clockwise movement to move the parts into collapsing position and to assume their original positions, as is shown in Fig. 2.

I claim:

1. In an ironing table, an ironing board and a collapsible supporting frame for the latter, said frame comprising a leg and a diagonal crutch, both pivotally connected to the board at one end of the latter, a jointed brace member pivotally connected at one end to the middle of said board and at the other to the leg, the crutch being provided with a laterally arranged member with which one element of said brace member slidably engages, a channeled fitting straddling the brace member, constituting the joint therein, and provided with web portions extending along the sides thereof and overhanging the latter, a bayonet joint formed in said overhanging portions of said webs, adapted when such supporting frame is extended, to engage said laterally arranged member. 95

2. In an ironing table, an ironing board and a collapsible supporting frame for the latter, said frame comprising a leg, a diagonal crutch and a jointed brace member, the leg and diagonal crutch being pivotally connected to the board at one end of the latter and the jointed brace member being pivotally connected at one of its ends to the board and at the other to the leg, the elements of such brace member when extended in supporting position defining substantially a right angle with each other, two fixed members arranged transversely of and carried by the crutch and spaced apart a distance greater than the thickness of said brace member and between which one element of the jointed brace member is maintained upon a relatively fixed path of travel and a stop carried by the brace member, with which stop one of the laterally arranged members engages when the supporting frame is fully extended. 105

3. In an ironing table, an ironing board and a collapsible supporting frame for the latter, said frame comprising a leg and a diagonal crutch, both members pivotally connected to the board at one end of the latter, a jointed brace member pivotally secured at one end to the middle of the board and at the other to the leg, said crutch being provided with a laterally arranged member with which one element of the brace member slidably engages, a channel fitting straddling the brace member constituting the joint therein, and provided with web portions extending along the sides thereof and overhanging the 110 125 130

latter, a bayonet joint formed in the over-hanging portions of the webs and adapted to engaging the laterally arranged member when the supporting frame is extended, and
5 a resilient member mounted adjacent said joint and in engagement with said laterally arranged member when the supporting frame is extended to hold said member in engagement with said joint.
